UNITED STATES PATENT OFFICE.

CHARLES E. PUTMAN, OF PORTLAND, OREGON.

AUTOMOBILE BED-PAD.

1,318,590.

Specification of Letters Patent.

Patented Oct. 14, 1919.

Application filed May 20, 1919. Serial No. 298,430.

To all whom it may concern:

Be it hereby known that I, CHARLES E. PUTMAN, a citizen of the United States, residing at Portland, in the county of Multnomah and State of Oregon, have invented 5 a new and useful Automobile Bed-Pad, of which the following is a specification.

My invention relates more particularly to that class of automobiles having seats with 10 removable backs upon which, in conjunction with the seats, is placed the pad.

The object of my invention is to provide a bed pad for an automobile arranged to make use of the seat cushions and backs as a 15 bed, and at the same time provide a cover for the bedding when rolled up for touring purposes, and also provide concealment, warmth and protection at the sides of the car, as well as for convenient receptacles for 20 clothing and equipment.

I attain these results in the manner illustrated in the accompanying drawing and set forth in the specification following.

Referring to the drawing, Figure 1 is 25 a side elevation of the device shown in section with its relation to an automobile body; Fig. 2 is a plan of Fig. 1; Fig. 3 is a transverse section through the car body looking toward the rear; Fig. 4 is a perspective 30 showing the appearance of the pad when rolled up for travel; Fig. 5 is a detailed plan showing the manner of joining the sides of the front and side curtains; Fig. 6 is a perspective of the pad itself with portions 35 broken away to show the appearance of the interior; Fig. 7 is a detailed plan of means for fastening the pad to the rear of the car; Fig. 8 is a front elevation of Fig. 7.

Similar letters and numbers of reference 40 refer to the same or similar parts throughout the several views.

Referring in detail to the drawing. A¹ is the canvas bottom of the pad. A² the rear portion of the side curtains, A³ is the 45 forward portion of the side curtains, the two side curtains being joined together by the flaps A⁴, which are secured by the buttons A⁵. The side curtains A² are joined at their rear edge to the rear curtain A⁶ by means of the flaps A⁷ and the buttons A⁸. The forward curtain A⁹ is joined to the forward edge of the side curtain A³ by the flaps A¹⁰ and the buttons A¹¹. Upon the upper edge of all of the side curtains are the buttons A¹². The rear end of the 50 canvas bottom A¹ is supplied with the rings

F¹ which are adapted to engage the hooks F² on the inside of the rear of the car. On the forward edge F³ of the canvas bottom A¹ are placed the straps F⁴ whose buckles F⁵ are adapted to engage the hooks F⁷ on the forward edge of the car, the loose end F⁶ of the straps F⁴ being of sufficient length to encircle the whole pad, as shown in Fig. 4.

The straps F⁴ may be arranged to make 65 the fastening adjustable to increase or decrease the tension on the canvas bottom A¹ without departing from the spirit of my invention.

Across the canvas bottom A¹ is placed the 70 flap H¹ which is sewed to the canvas bottom A¹ along with the edge H², the edge H³ being supplied with the snaps H⁴ which are adapted to hold the lower edge of the bedding, H⁵.

It will be observed that the forward curtain A⁹ does not fasten to the forward edge of the canvas bottom A¹, but joins it at a point almost directly underneath the wind shield. It will be necessary to divide the 80 forward curtain A⁹ to admit the steering wheel.

On the inside faces of the side curtains A² and A³ and the rear curtain A⁶ and somewhat above the canvas bottom A¹ are located 85 the side pockets H⁶ which are adapted to contain articles of wearing apparel, mosquito bar and general equipment.

K¹ is a soft pad adapted to occupy the full width of the canvas bottom A¹ from the rear 90 end of the car to the edge H² of the member H¹. It will be seen in Fig. 3 that the sides of the pad K¹ are not secured to the canvas bottom A¹ but are constructed so as to permit the bedding H⁵ to be tucked underneath 95 the edges of the soft pad K¹.

The portion K² of the canvas bottom A¹ is not required for bed room and may be used for storage space, both above and below same.

It will be observed in Fig. 3 that the portions of the side curtains A² and A³ which extend above the top of the pockets H⁶ may be held away from close contact with the automobile top side curtains by means of the 105 straps H⁷, which are supplied with the buttons H⁸ in a manner to hold the side curtains of my device in the way I have illustrated, in order to insure ample ventilation for the occupants without exposing them to 110 passersby.

While I have thus illustrated and de-

scribed my invention it is not my desire to limit myself to this precise form or method of application of my device, but intend that it shall cover all forms and modifications 5 that fall fairly within the appended claim.

What I claim as new and desire to protect by Letters Patent of the United States, is:

An automobile bed pad, consisting of a body portion adapted to cover the seats of 10 the car, said body having a mattress covering secured to same in a manner which will permit the tucking in of the covers on the sides and foot portions of the bed, side flaps extending from each of the four sides of the

body member in a manner that they may 15 entirely inclose the sides of the car and be secured thereto and to each other, a ventilating means consisting of hangers suspended from the bows of the top, said hangers being arranged to fasten to the 20 upper edge of a side flap and hold the upper portion of it away from the side of the car in a manner to admit air, and a door means consisting of an opening formed in a side flap directly in front of a door latch, said 25 opening having suitable means for fastening in place.

CHARLES E. PUTMAN.
